UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,830, dated November 5, 1895.

Application filed September 30, 1895. Serial No. 564,216. Term of patent 31 years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

○ The design consists of a series of ornaments of Grecian style, with ornamental scrolls springing from the base of said ornaments and cornucopia-like figures on each side of said ornaments filled with flowers and leaves, 5 and small festoons of flowers and leaves hanging from the ornamental scrolls below said ornaments, as represented in the accompanying drawing. The border of the de-

sign is also formed of said ornaments of Grecian style, with ornamental scrolls springing 20 from the base of said ornaments and cornucopia-like figures on each side of said ornaments filled with flowers and leaves, and torch-like figures between said ornaments, as shown in the drawing. 25

What I claim is—

1. The design for wall paper herein shown and described.
2. In the design for wall paper, the border herein shown and described. 30

Witness my hand this 27th day of September, 1895.

CHARLES BOOZ.
